UNITED STATES PATENT OFFICE.

CONRAD WUNDERLICH, OF MCKEESPORT, PENNSYLVANIA.

MOLD FOR INGOT MOLDS.

Application filed February 23, 1926. Serial No. 90,118.

This invention relates to improvements in molds for ingot molds.

In making molds of the type above mentioned in accordance with the practice of the prior art, it has always been customary to use a solid mold and a solid core and line the mold with molder's earth in order to provide for the molding of lugs and eyes on the exterior of the mold so that suitable handling apparatus may be connected with the mold in use during the making of ingots. This operation requires a substantial number of men for lining the molds with the earth in preparing the mold for making an ingot mold in addition to a large amount of labor in removing the ingot mold and cleaning both the ingot mold and the mold therefor, at the end of each operation.

It is the object of the present invention to substantially simplify the method of making ingot molds by providing a special form of mold whereby the eyes and lugs may be provided on the ingot mold in the making thereof without using molder's earth and by molding directly in the main mold and thereby eliminating a large amount of labor incident to the making of these ingot molds.

The invention comprehends numerous other objects residing in the details of construction and association of parts which are more particularly pointed out in the following description and in the claims directed to a preferred form of the invention, it being understood however, that various changes may be made in the size, shape and arrangement of these parts without departing from the spirit and scope of the invention as herein set forth.

In the drawing forming part of this application:

Figure 1 is a side elevation of the improved mold of this invention.

Fig. 2 is a side elevational view of the mold taken at right angles to Fig. 1.

Fig. 3 is a view of the mold with one section removed showing the ingot mold in section and the core in elevation.

Fig. 4 is an inside elevation of one mold section illustrating the interior construction thereof.

Fig. 5 is a horizontal sectional view taken on the line 5—5 of Fig. 1.

This invention is specially designed for the making of ingot molds as distinguished from molds for making the ingots themselves. This mold comprises a pair of co-

operating half sections 1 and 2 respectively which are formed at their meeting faces with outwardly extending flanges 3 provided with a plurality of registering openings 4 adapted to receive slotted bolt members 5 which in turn receive wedge members 6 for locking the mold sections in assembled relation as shown in the drawing.

The mold sections 1 and 2 are each formed with a molding recess 7 shaped to provide the desired contour to the outer wall of the ingot mold. These recesses have tapered side walls as indicated at 8 to permit the ready removal of the ingot mold after casting from each half section 1 and 2 of the mold.

The abutting faces of the mold sections 1 and 2 are recessed as indicated at 9 beyond the recesses 7 to form the lugs on the ingot molds, the recesses 9 in each half section cooperating and forming one-half of each lug. In the central portion the mold is formed with a V-shaped groove 10 at one side of the recesses 7 to receive and mount the eye or bail 11 in proper position between the mold sections so that it will be cast into the ingot mold. Openings 12 are formed in the central portion of each side wall of the mold sections 1 and 2 which are plugged as shown in Fig. 5 during the making of the ingot mold, the plugs being removable so that the plunger of an ejecting apparatus may be used for ejecting the ingot mold formed from each mold section in the event it sticks.

The mold sections 1 and 2 are provided in the central portion of each side with lugs 13 so that each section may be suitably gripped by the ejecting apparatus for supporting the mold sections during the ejection of the ingot mold formed therein. These mold sections 1 and 2 are further formed with lugs 14 at the ends to receive the hoisting apparatus used to transport the mold sections from place to place.

The core for the ingot molds indicated at 15 which is made in the shape of the ingot and is provided with a tapered section 16 to form an ingot mold commonly known as a bottle type.

In making an ingot mold for this improved mold structure the bail 11 is placed in the groove 10 and the mold sections 1 and 2 assembled as shown in Figs. 1 and 2 with the bail locked in position between the sections by securing the slotted bolts in the openings 4 with the wedges 6. The open-

ings 12 are plugged as shown in Fig. 5 and the core 15 positioned within the mold in the proper position as shown in Fig. 3. The mold is set on its end as shown in the drawings in a well known manner and the metal poured in the top of the mold to form the ingot mold as shown in Fig. 3. This metal will flow into the recesses 9 formed by the mold sections when locked in cooperative position so that the lugs will be cast onto the mold body. The mold may then be removed with the metal cast therein to permit sufficient cooling and hardening of the ingot mold after which the mold sections 1 and 2 may be readily removed by removing the wedges 6 of the bolts 5 and then separating the sections 1 and 2 from the ingot mold using the ejecting apparatus when necessary. The ingot mold with the core 15 is then removed to a suitable point and the core removed with suitable ejecting apparatus already well known in the art.

The construction of the ingot mold in sections thereby permits the ready positioning of the bail and the formation of the lugs on the ingot mold and the easy removal of the mold sections from the ingot mold after formation which entirely eliminates the use of sand or other form of molder's earth for the making of the ingot mold and also all of the labor in connection with the molding of the sand in preparing the ingot mold and the cleaning of the molds as now required for the making of these ingot molds. The provision of the lugs 13 and the openings 12 also permits of the ready attachment of an ejecting apparatus to each mold section for readily ejecting the ingot mold from the section.

Having thus described my invention, what I claim as new is:

1. An outside mold for ingot molds comprising a pair of duplicate sections adapted

to be secured together in assembled relation, each section being formed with longitudinally disposed cooperating trough like recesses in the abutting faces thereof and forming a hollow exterior for the outside mold opening at each end thereof and within which to pour the material for molding the body portion of an ingot mold and a core disposed longitudinally in the hollow portion of the outside mold in spaced relation from the walls of each section and having one end extending outwardly of said outside mold whereby to form a tubular ingot mold within said outer mold upon the threading of the material poured therein, the adjacent portions of the abutting faces of said sections being formed with cooperating laterally disposed recesses communicating with said first named recesses and adapted to form lugs on the outer face of the ingot mold.

2. An outside mold for ingot molds comprising a pair of mold sections formed of rectangular block members adapted to be secured together in assembled relation, each section having a longitudinal channel in one face thereof, the side walls of said channel being inclined inwardly toward the bottom thereof, said channel cooperating to form a hollow bore through said outside mold and opening at each end thereof whereby to receive ingot molds forming material poured in one end thereof for molding the body portion of an ingot mold and a core disposed longitudinally in said bore in spaced relation from the walls thereof and having one end extending outwardly of said outside mold whereby to form a tubular ingot mold within said outside mold, upon the setting of the material toward their end.

In testimony whereof I affix my signature.

CONRAD WUNDERLICH.
